UNITED STATES PATENT OFFICE.

WALTER L. BRADSHAW, OF CAMBRIDGEPORT, MASSACHUSETTS, ASSIGNOR,
BY MESNE ASSIGNMENTS, TO JOHN E. R. HAYES, OF MELROSE, MASSA-
CHUSETTS.

PENDANT ELECTRIC FIXTURE.

No. 857,024.

Specification of Letters Patent.

Patented June 18, 1907.

Application filed August 29, 1903. Serial No. 171,309.

To all whom it may concern:

Be it known that I, WALTER L. BRADSHAW, a citizen of the United States, residing at Cambridgeport, in the county of Middlesex, State of Massachusetts, have invented a new and useful Improvement in Pendant Electric Fixtures, of which the following is a full, clear, and exact description, reference being had to the accompanying drawings, forming part of this specification and explaining its nature.

My invention has for its object the protection of pendant electric fixtures whereby the weight of a lamp or other electrical translating device may be sustained positively by the conducting cord, thereby taking the weight off of the binding terminal screws of the fixture and affording relief from all strains.

It is well known that unless some means are provided for relieving the binding screws of an electric fixture from the strain of the weight of the conducting cord and the lamp, the line terminals are likely to be torn out, causing short circuiting and a burning out of the fixture, and, in many instances, fire. The means now generally in use for relieving the binding screws are imperfect and unsatisfactory. Although defective and undesirable in many ways, the means referred to still continue in use for want of a more efficient construction. Briefly, such means consist of a simple knotting of the cord above the base and inside of the cap at the socket piece of the fixture, and in the case of the ceiling rosette, inside the rosette below the terminal screws. The practical objections to the knot are many. If the lamp and cord have considerable weight the knot may fail to hold at all, or the cords may become cut or so worn away as to ultimately cause short circuiting. The double knot, and even a single knot, is objectionable in that it often prevents the base from being properly pushed up into place in the socket. Moreover, while the use of the knot is objectionable in such junction fixtures as rosettes and lamp sockets, in other junction fixtures, such, for instance as plugs, the use of the knot is practically impossible because space for the same is entirely lacking. At best, the knot can be relied on to support but a few pounds. Other objections to the knot are that it is ordinarily entirely concealed from view and cannot be

seen until the socket has been taken apart; 55 and that although it is now required by all underwriters, as a matter of fact, electricians will not uniformly take the trouble to make the knot, but will instead attach the cords directly to the binding posts of the junction device, and inspectors will not take the trouble to take the fixings apart to see that the knots have been tied. The result is often fire and serious loss.

My invention, specifically, consists of a 55 clamp in the nature of a chuck grip, which is adapted to be screwed into, otherwise attached to the ceiling rosette or to the lamp socket, or other junction devices. The cord for the conducting wires passes through the 70 clamp, and upon proper manipulation the clamp positively engages the cord. The advantages of my clamp are that the cord is not so liable to be jammed or cut. The gripping surface of the clamp may be of considerable extent, and of a nature to grip the cord uniformly, distributing the strain more equally over the lamp cord and thereby sustaining greater weights. When the clamp is released from contact with the cord, the 80 cord may be moved in either direction through the clamp. The clamp is attached to the cord in plain view and can be readily tested by an inspector as to its operativeness. It may also be of a neat and attractive design 85 and thus add to the appearance of the fixture.

For a further and more detailed description of my device for relieving the strain on the conducting wire terminals of the electrical translating device, reference may be had 90 to the accompanying drawings, in which:

Figure 1 is a side elevation of the lamp support, the parts being assembled and detached from the terminal fixture. Fig. 2 is a view in elevation of one of the parts of my device, 95 being in the nature of a cup provided with a threaded nipple for attachment to the terminal fixture. Fig. 3 is a view in elevation of another detail of my device, the same being a split sleeve adapted to be inserted within the 100 piece shown in Fig. 2. Fig. 4 is a view in elevation of the third detail of my device, the same consisting of a cap adapted to engage the cup shown in Fig. 2 and also to engage the sleeve shown in Fig. 3 to force said sleeve 105 within said cup. Fig. 5 is a sectional view of the lamp supporting clamp in co-operative relation to a ceiling rosette, which is also

shown in section, together with the cord which is shown as passing through the clamp and attached to the rosette. Fig. 6 is a top plan view of the split sleeve and its clamping jaws shown in elevation in Fig. 3. Fig. 7 is a bottom plan view of a modified rosette to which my lamp supporting clamp may be attached. Fig. 8 is a perspective view of the conducting cord, my lamp supporting clamp, a socket and Edison lamp, all in coöperative relation.

My lamp supporting clamp, as before stated, is shown assembled in perspective in Fig. 1, and it is comprised of three parts, as shown in Figs. 2, 3 and 4, namely, a hollow shell or cup-like member, a chuck member formed on the split sleeve, and an encircling top or cap, all as heretofore mentioned.

Referring to Figs. 2 and 5, a hollow cup-like shell or chamber 1 is provided with a hollow extension 2 forming a nipple or neck through which the conducting cord or other wire carrying means is adapted to pass. The extension 2 is shown threaded whereby the supporting clamp may be screwed to the rosette, or to the lamp socket, as the case may be. The inside wall of the cup, as shown at 3 in Fig. 5, flares or slopes outwardly away from the neck 2 for the purpose presently to be described. The chamber or cup is provided with a rim or cylindrical extension 4 and at its extremity it is provided with screw-threads 5 for the adjustable attachment of an inclosing cap.

The form of clasp forming part of my supporting device is shown in Figs. 3 and 5. It is composed of a sleeve or bushing 6 of cylindrical shape having a passage 7 for the conducting cord. Said bushing is of insulating material. The edge of the passage is rounded in the usual way, as at 7', to prevent wearing and cutting of the cord at this point. The bushing or sleeve is fitted at right-angles to form the tongues or clasping fingers 8. These tongues when in their free normal condition allow the conducting cord to pass easily back and forth between them. The extreme ends of these tongues are so formed as to present an interrupted circular flange or lug 9, the outer surface 10 of which is tapered or beveled inwardly and away from the bushing at a definite angle. I have shown the tongues as preferably cut inwardly or scooped out, as at 8', between their extremes. This, however, is for the purpose of giving them an increased resiliency and is not an essential feature of their construction. At the juncture of the tongues or at the point of their attachment to the bushing is provided an integral flange or shoulder 11. The bushing and clamping fingers are preferably of wood or other suitable insulating material throughout. This, however, may be subject to some variation, as hereinafter indicated. While I have shown the bushing 6 as integral with

the tongues 8, this, of course, is not necessary. The tongues may be attached to the bushing in any suitable manner.

In Fig. 4 a cap for operating and retaining the clasping means is indicated by 12. The cap is provided with an annular flange 13, interiorly threaded as shown at 14. The threads 14 of the cap engage the threads 5 of the cup shell or casing for the purpose presently to be specified. The cap is provided with a central opening 15 of sufficient size to permit it to be slipped over the sleeve or bushing 6 and to engage the shoulder 11 thereof. It is also preferably provided with a milled flange 15' whereby it may be conveniently turned.

In operation the bushing and its clasping tongues are slipped into the cup or casing. The cap is then slipped over the bottom of the bushing and turned so as to slightly engage on the threads of the cup. The conducting cord is then passed into the opening 7 and through the clasping tongues and the cup or casing and is then properly secured to the line terminals. The screw-threaded nipple of the cup is then tightly screwed into the terminal support, whether it be a socket piece or a rosette, as presently to be described. It may be held tight by a setscrew as shown at 30. Then upon further turning of the cap upon the cup, the cap engages the shoulder 11 of the bushing and forces it into the chamber of the cup, causing the beveled edges 10 of the tongues of said bushing to engage the flaring wall 3 of the cup. The ends of the tongues passing along the wall 3 are thereby forced inward so as to tightly embrace the cord. The bevel at the ends of the tongues is such that when the grip is in its locking position the beveled faces of the tongues contact throughout their length with the wall. The tongues are also preferably so mounted upon the bushing 6 that when in their final and locking position they engage the cord throughout their entire length, thus presenting to it a large and uniform gripping surface. It is, therefore, apparent that when in their free and normal position the tongues have a slight angular inclination outward. The threaded extension or nipple 2 of the cup 1 is, as above stated, adapted to interlock with the threaded extension of an ordinary Edison lamp or other fixture. It is possible, however, that the interlocking of the cup and the fixture may be accomplished by other than threaded means, but any such like slight modification falls entirely within the scope of my invention.

Although the cup or casing is adapted for immediate attachment to the ordinary socket fixture, as above described, yet when used in connection with a ceiling rosette, a slight modification of the structure of such rosette is generally necessary.

The ordinary porcelain ceiling rosette is provided with a circular opening for the passage of the conducting cord. This, as is obvious, can offer no means for engagement with the threaded extension of my lamp supporting device. In Figs. 5 and 7 I have shown substantially the form of porcelain rosette 16 commonly used. Instead, however, of the ordinary central circular opening common to rosettes, I have provided an opening, a portion of which is made square to provide a chamber 17. The lower extremity 18 of the central opening I have shown as round, and of less diameter than the square chamber just mentioned. I thus provide a ledge or flange 19. Within the square chamber I have shown a square nut 20. The threaded portion 21 of the nut is of a diameter to engage the thread of the extension 2 of the cup. Said extension of the cup upon being inserted through the circular opening 18 of the rosette (see Fig. 5) and turned to engage the nut, is held in place and prevented thereby from being withdrawn. Whereas I have shown my chamber 17 as of square shape, it is obvious that such shape is not essential. The chamber may be of any other angular or irregular form, the only requisite being that it shall be of a shape to receive a nut 20 and prevent the same from turning within it.

My hollow cup or casing 1 is preferably of brass or similar material, although this is not essential. When, however, it is of metal I provide the opening in the extension 2 with an interior bushing 25 of insulating material. This is clearly shown in Fig. 5, and is seen to be provided with an interior outwardly extending flange to engage the end wall of the cup, and extends slightly beyond the extreme end of the part 2, preferably about one-thirty-second (1/32) of an inch. This insulation, together with the insulating nature of the bushing 6 and the tongues 8, insure the fixture from short circuit in case the cord is worn at any point of its contact with the clasp.

Claims.

1. In incandescent electric light fixtures, the combination with a support for the electric wire terminals of a device for supporting the lamp from the conducting cord, said device comprising a tapering or cone shaped shell, a sleeve extending into the shell and slotted to form clamping fingers said sleeve having a continuous retaining flange to which the fingers are attached to render the

same unitary or integral in construction, a cap covering the slotted portion of the sleeve and the shell and adapted to force the fingers 60 against the walls of the shell to compress the fingers against the conducting cord, and means to attach the supporting device to the support for the electric wire terminals.

2. In a device of the character described, a 65 lamp supporting device provided with means of attachment to the support for the electric wire terminals, said device comprising a tapering shell or casing, a slotted sleeve movable in the shell the slits in the sleeve forming 70 yielding clamping fingers, cam shoulders on the fingers and means for forcing the sleeve into the shell and the cam fingers against the tapering sides of the shell whereby they may be compressed against the conducting cord 75 when said cord is passed through the supporting device.

3. A device for relieving the terminal connections of electrical translating devices from strain, comprising a hollow tapering or cone 80 shaped shell or casing open at each end for the passage of the conducting cord and having at one end a screw threaded neck or nipple to engage the rosette or lamp socket and at its other end with an extended rim for the 85 connection of a cap, a hollow block having clamping jaws to engage the conducting cord and a cap piece adjustable on the rim of the casing and adapted to force the block into the casing and the jaws against the tapering 90 sides of the casing to compress them against the conducting cord so that the weight of the lamp may be taken from the terminals.

4. A device of the character specified having a hollow shell or casing provided with a 95 sloping interior wall and through which the connecting cord or wire is adapted to pass, a cord-clamping member or members inside said shell or casing adapted in part when pressed into the casing to engage with the 100 sloping wall thereof and thereby be made to engage with the connecting cord or wire, a hollow insulating bushing on said cord or wire connecting with said clamping member or members, and a cap piece connecting with 105 and adjustable on the rim of the casing and adapted to force said bushing toward or into the shell or casing and said clamping member or members against the sloping sides thereof.
